UNITED STATES PATENT OFFICE.

JAMES J. HENNESSY, OF NEW YORK, N. Y.

JOURNAL LUBRICATOR.

Application filed September 20, 1921. Serial No. 501,869.

To all whom it may concern:

Be it known that I, JAMES J. HENNESSY, a citizen of the United States, residing at New York city, New York, have invented a certain new and useful Improvement in Journal Lubricators, of which the following is a full, clear, and exact description, such as will enable others skilled in the art to which it appertains to make and use the same, reference being had to the accompanying drawings, forming part of this specification.

My invention relates to journal lubricators such as are used in railway rolling stock, and consists in an improved lubricant reservoir and pump construction adapted to be applied to journal boxes and to be operated by the relative movement between the axle journal and the journal box.

One of the objects of my invention is to provide a lubricator which may be assembled with a standard journal box without necessitating any work on the latter.

An additional object is to utilize the bottom of the journal box for a wall of the lubricant reservoir, thereby reducing the amount of material required for the lubricator accessory.

An additional object is to provide a lubricator which may be applied to and removed from the journal box while the axle journal is assembled therewith.

A still further object is to so construct my lubricator that the journal box may be jacked up while mounted on the journal to permit replacement of the brasses and wedges.

In the accompanying drawings, which illustrate a selected embodiment of my invention,—

Figure 1 is a longitudinal vertical section through the lower portion of a journal box with my lubricator applied and showing the axle journal assembled therewith.

Figure 2 is a transverse vertical section on line 2—2 of Figure 1.

Figure 3 is a detail horizontal section on line 3—3 of Figure 1.

Figures 4 and 5 are similar to Figures 1 and 2 which show a modification of my invention.

The lubricator body 1 consists preferably of a casting adapted to rest upon the bottom of the journal box 2 and to extend upwardly toward the opening in the journal box and engage the inside wall of the latter

at 3 adjacent to its opening. A sheet metal member 4 is secured to body 1 at a point spaced from the bottom of the journal box and extends outwardly from the body to 60 the side walls of the journal box. The contact between member 4 and the journal box wall may be made oil-tight by means of packing 5 or by a resilient pressure on the wall as indicated at 6. The space between body 1, 65 members 4, and the bottom of the journal box forms the lubricant reservoir.

Integral with body 1 is the pump cylinder 7, open to the lubricant reservoir, disposed horizontally and provided with a 70 pump plunger 8 having a curved extension 9 on its outer end. A lever 10 is pivoted to the body 1, engages the end of extension 9, and projects beyond body 1 to a point approximately opposite the axis of a journal 75 assembled with the box. An element 11 is pivoted to the outer end of lever 10 and is adapted to engage a center hole 12 in the journal and to transmit shifting movement of the journal in one direction through 80 lever 10 and extension 9 to plunger 8. Movement of plunger 8 in the opposite direction is provided by a spring 13 compressed between a shoulder at the outer end of cylinder 7 and an opposing shoulder 85 on the plunger.

The pivoting of element 11 on lever 10 permits relative vertical movement of the journal and the journal box without effecting the lubricator. I prefer to make element 90 11 so that in emergency it will yield to the shifting movement of the journal to prevent injury to the pump mechanism.

The intake to cylinder 7 is provided with a suitable check valve 14 and the discharge 95 from cylinder 7 is through a passage in an upwardly extending lug 15 which is provided with a check valve 16. Telescopically mounted in lug 15 is a bushing 17 adapted to bear against the bottom of the journal irrespective of the vertical position of the latter. A spring 18 compressed between the valves 16 and suitable tongues on bushing 17 serves at once to press both bushing and valve to their desired positions.

It will be noted that the lubricator has no bottom and cooperates with the bottom of the journal box to form the lubricant reservoir. This construction provides a comparatively shallow lubricator which permits 110 the journal box to be jacked up in the usual manner when it is desired to remove the

journal brass. When this operation is performed, the supporting portion 2 of the body 1 and the top of lug 15 engage the bottom of the journal box and the axle journal, respectively, to limit the movement of the journal and box toward each other and prevent injury to the lubricator.

Waste may be packed over the top of the lubricator in the usual manner and the construction is such that the car may be reversed on a dumping machine without loss of oil, which is an advantage not present in many types of lubricators.

In the modification shown in Figures 4 and 5, the pump cylinder 19 and housing 20 is formed integral with the journal box and the pump plunger 21 is operated by means of a rock 22 and gears 23 and 24. The latter are journaled in housing 20 and are driven alternately in opposite directions by a segment gear 25 forming one end of a lever 26 which is fulcrumed in the upper end of housing 20 and is reciprocated by the contact of element 27 with the end of the axle journal. The upper face of housing 20 is slotted at 29 to permit the insertion of gears 23 and 24 and of the segment gear 25. A waste holder 28 is mounted on the journal box and on housing 20 similarly to the waste holder 4 shown in the preferred construction.

The principle of operation of this modification is the same as that of the preferred construction and the essential features of the latter are retained.

Other changes in the construction of my device may be made, without departing from the spirit of the invention, as set forth in the following claims.

40 I claim:

1. In combination, a railway axle journal, a standard journal box carried thereby, a member cooperating with the bottom of said box to form a closed lubricant reservoir, a telescoping passage leading from the reservoir formed to said journal and adapted to accommodate variations in the vertical position of said journal, and a pump operated

by relative horizontal movement of said box and journal for feeding lubricant through said passage.

2. In a lubricator, a body member adapted to be positioned on the bottom of a standard railway journal box to form a lubricant reservoir, a downwardly extending support on said member, an upwardly extending lug on said member adapted to limit upward movement, relative to a journal, of said body and a journal box assembled therewith, a bushing telescopically mounted in said lug, and a lubricant passage from said reservoir to said lug and bushing.

3. In a journal lubricator, a lubricant reservoir, a pump cylinder open thereto, a pump plunger reciprocally mounted in said cylinder and extending outwardly therefrom into said reservoir, a spring compressed between the end of said cylinder and the outwardly extending portion of said plunger, and a member extending outside of said reservoir and adapted to be operated by movement of a journal relative to the reservoir for operating said plunger to compress said spring.

4. In a journal box, a lubricant reservoir, a pumping mechanism, and a rigid element adapted to be supported upon the bottom of a journal box and extending above said reservoir, whereby when the journal box is jacked up relative to a journal with which it is assembled, said element will engage the journal and prevent injury to said reservoir and pumping mechanism.

5. In a journal lubricator, a lubricant reservoir, a pump cylinder, a discharge passage therefrom, a check valve in said passage, a telescoping extension of said passage adapted to contact with the surface of a journal to be lubricated, and a spring compressed between said check valve and extension to press the valve toward its seat and the extension toward its projected position.

In testimony whereof I hereunto affix my signature this 29th day of June, 1921.

JAMES J. HENNESSY.
